CLAIM

The ornamental design for prostheses, as shown and described.

DESCRIPTION

FIG. 1 is a first side view of prostheses in accordance with aspects of the present disclosure.

FIG. 2 is a front view of the prostheses in accordance with aspects of the present disclosure.

FIG. 3 is a second side view of the prostheses in accordance with aspects of the present disclosure.

FIG. 4 is a top view of the prostheses in accordance with aspects of the present disclosure.

FIG. 5 is a perspective view of the second side of the prostheses in accordance with aspects of the present disclosure.

FIG. 6 is a perspective view of the first side of the prostheses in accordance with aspects of the present disclosure; and, FIG. 7 is a rear view of the prostheses in accordance with aspects of the present disclosure.

Applicant expressly reserves the right to modify FIGS. 1-7 to show in solid lines any of the features shown in FIGS. 1-7 in dashed-lines; and to show in dashed-lines any the features shown in FIGS. 1-7 in solid lines. Any subject matter shown in dashed lines, and any surfaces of the design not shown, including interior surfaces, form no part of the claimed invention.
